UNITED STATES PATENT OFFICE.

FRANK MUMFORD SEARS, OF EAST SAGINAW, MICHIGAN.

DOOR-CHECK.

SPECIFICATION forming part of Letters Patent No. 296,229, dated April 1, 1884.

Application filed January 12, 1884. (No model.)

To all whom it may concern:

Be it known that I, FRANK M. SEARS, of East Saginaw, in the county of Saginaw and State of Michigan, have invented a new and 5 Improved Door Check and Holder, of which the following is a full, clear, and exact description.

The object of my invention is to provide a new and improved device for holding a door 10 open, and for preventing the door from being opened too far.

The invention consists in the combination, with a stud secured to and projecting from the door, of a block provided with a transverse 15 and a vertical aperture, a pin or bolt being held in the lower part of the vertical aperture in such a manner that it projects into the transverse aperture, a spring resting on the pin or bolt, and which spring can be adjusted 20 by means of a screw screwed to the upper part of the vertical aperture.

Reference is to be had to the accompanying drawings, forming part of this specification, in which similar letters of reference indicate 25 corresponding parts in all the figures.

Figure 1 is a longitudinal sectional elevation of my improved door-check, showing how it is applied. Fig. 2 is a face view of the part on the door. Fig. 3 is a face view of the part 30 secured on the floor.

A stud, A, projects from a plate, B, secured to the outer surface of the door, at the bottom edge, which stud is slightly recessed in its upper surface. A block, C, provided with a 35 base plate, D, is provided with a transverse aperture, E, and with an aperture, F, extending from the top down to the transverse aperture E, which aperture F is contracted at the lower end to form a shoulder, a. A short

pin or bolt, G, having a flat head, H, is contained in the lower part of the aperture F in such a manner that the head H rests upon the flange *a* and the lower rounded end of the pin or stud projects into the aperture E. A spring, K, rests on the stud or pin G, and a screw, J, is screwed into the upper part of the aperture E. The spring K is pressed down on the head of the stud or pin G, and is confined between the said pin by the screw J. The tension of the spring can thus be adjusted 40 by screwing the screw J down more or less. If a heavy door is to be held open, the spring must be adjusted to have more power and offer more resistance than if a light door is to be held. If the door is swung open, the stud 45 A passes into the aperture E and presses the stud G upward slightly, and then the spring K presses the stud on the recessed part of the stud A, and thus holds the door open. If the door is to be closed, the stud A is drawn out 50 of the aperture E by pulling or pushing on the door.

The block C can be secured to the wall, if desired.

Having thus described my invention, what 55 I claim as new, and desire to secure by Letters Patent, is—

In a door-check, the block C, provided with the transverse aperture E and the vertical aperture F, combined with the pin or bolt G, 70 held in the aperture E, the spring K, resting on the bolt or pin G, and the screw J, screwed in the upper part of the aperture F, substantially as herein shown and described.

FRANK MUMFORD SEARS.
